UNITED STATES PATENT OFFICE.

LEE A. MILLER, OF MILWAUKEE, WISCONSIN, ASSIGNOR TO SAMUEL B. FULLER, OF WATERTOWN, WISCONSIN; MARY B. FULLER ADMINISTRATRIX OF SAID SAMUEL B. FULLER, DECEASED.

TENSION FOR SEWING-MACHINES.

SPECIFICATION forming part of Letters Patent No. 657,350, dated September 4, 1900.

Application filed September 25, 1899. Serial No. 731,589. (No model.)

To all whom it may concern:

Be it known that I, LEE A. MILLER, a citizen of the United States, and a resident of Milwaukee, in the county of Milwaukee and State 5 of Wisconsin, have invented certain new and useful Improvements in Sewing-Machines; and I do hereby declare that the following is a full, clear, and exact description thereof.

My invention consists in certain peculiarities of construction and combination of parts constituting a sewing-machine spool-thread tension mechanism and means for releasing the same, as hereinafter particularly set forth with reference to the accompanying drawings, 15 and subsequently claimed.

Figure 1 represents a vertical longitudinal section of a portion of a sewing-machine head provided with my improved spool-thread tension and release mechanism; Fig. 2, a transverse section of the same on the plane indicated by line 2 2 in the preceding figure; Fig. 3, a detail plan view illustrating said tension and release mechanism partly in horizontal section; Fig. 4, a detail horizontal section on the plane indicated by line 4 4 in the first figure; Fig. 5, a detail elevation of the needle end of the sewing-machine head partly broken, the face-plate being detached and certain parts not related to my present improvements omitted, the view being indicated by line 5 5 in said figure; and Fig. 6, a detail elevation illustrating the presser-foot lifter of said sewing-machine head at its greatest elevation in working contact with a lever constituting part of the means for releasing tension on the spool-thread.

Referring by letter to the drawings, A indicates a portion of the arm of a sewing-machine head provided with an upper elongate 40 socket-bracket B, that constitutes a seat for a spool-thread pincer C, this pincer being a strip of spring metal bent to form meeting jaws b, having their extremities turned outward in opposite directions clear of said bracket adjacent to a groove c therein. The socket portion of the bracket is provided with an inner lug d in opposition to the spool-thread pincer back of its jaws. A screw D, engaging the bracket and pincer, is provided

with a shoulder e, that bears against said pincer opposite the bracket-lug aforesaid and adjustment of the screw regulates the tension of the pincer-jaws b upon the spool-thread.

Trunnioned in a tubular vertical branch f 55 of the socket-bracket B is a rocker E, provided with a wedge-shaped spur g, arranged in rear of the meeting jaws b of the pincer B to spread said jaws apart when the upper portion of the rocker is tilted forward, whereby tension on the spool-thread is released. It is preferable, as herein shown, to provide the wedge end of the rocker with an upwardly-extending hook h, that constitutes a guide and serves to prevent upward slip of 65 the spool-thread from the tension device, consisting of the screw-controlled pincer above specified. If desired, an eye may be substituted for the hook. The depending shank i of the rocker E is joined to a link-rod F, that 70 has free play in a solid portion of the machine-arm longitudinally of the same, and the other end of the rod is joined to an angular lever G, fulcrumed in said machine-arm and having its free end extended outward through 75 a slot in the same to come in the path of the lifter H for the pivotal presser-foot I of the machine when said lifter is swung in the direction necessary to the greatest elevation of said presser-foot.

The mechanism herein shown for actuating the rocker E or spool-thread tension-release is similar to what is shown in Patent No. 572,557 of December 8, 1896, and like in said patent I show the shank J of the presser-foot 85 I provided with a rigid head-sleeve K, having a block extension or lug j, that is loose in a slot k in the vertical face of the machine-arm, this lug being in opposition to the cam end of the pivotal lifter H, above specified. 90

The adjustable spool-thread tension device herein set forth may be utilized independent of release mechanism, and the details of this mechanism may differ from what is shown and described in this application without departure from what I seek to cover.

The groove c in the bracket B is sufficiently wide to permit of the jaws b of the screw-

controlled spool-thread tension device yielding in opposite directions to knots or other irregularities in the thread, and thus the latter will more readily feed through said tension device. The action of the tension-release mechanism being automatic and positive, work may be readily removed from the sewing-machine or the bobbin wound without taking the spool-thread from the needle.

10 Having thus described my invention, what I claim as new, and desire to secure by Letters Patent, is—

1. In a sewing-machine the arm thereof provided with an upper elongate forwardly-grooved socket-bracket, a bent spring-metal plate seated in the bracket and constituting a spool-thread pincer having the jaws thereof expandible in the bracket-groove, and means for regulating tension of the pincer.
2. In a sewing-machine the arm thereof provided with an upper elongate forwardly-grooved socket-bracket, a bent spring-metal plate seated in the bracket and constituting a spool-thread pincer having the jaws thereof expandible in the bracket-groove, an inner bracket-lug opposing the pincer back of its jaws, and a pincer and bracket engaging screw having a shoulder opposing said pincer opposite said bracket-lug.
3. In a sewing-machine the arm thereof provided with an upper elongate forwardly-grooved socket-bracket, a bent spring-metal plate seated in the bracket and constituting a spool-thread pincer having its jaws expandible in the bracket-groove, means for regulating tension of the pincer, and other means operative in conjunction with the

presser-foot lifter of the machine to automatically spread the pincer-jaws.

4. In a sewing-machine the arm thereof provided with an upper elongate forwardly-grooved socket-bracket, a bent spring-metal plate seated in the bracket and constituting a spool-thread pincer having the jaws thereof expandible in the bracket-groove, means for regulating tension of the pincer, a rocker trunnioned in a tubular vertical branch of said bracket and provided with a wedge-shaped spur arranged directly in rear of the pincer-jaws, a shank depending from the rocker, an angular lever fulcrumed inside the machine-arm and having one of its ends extending outward through a slot in said arm to come in the path of the presser-foot lifter of said machine when this lifter is swung up, and a link-rod connecting the rocker-shank and other end of said lever.

5. In a sewing-machine the arm thereof provided with a spool-thread spring-pincer adjustable as to tension, a rocker constituting a spreader for the pincer-jaws, a spool-thread guide forming part of the rocker, and means operative in conjunction with the presser-foot lifter of the machine to actuate said rocker.

In testimony that I claim the foregoing I have hereunto set my hand, at Milwaukee, in the county of Milwaukee and State of Wisconsin, in the presence of two witnesses.

LEE A. MILLER.
